STOP POSITIONING MECHANISM FOR
TYPEWRITERS

William F. Helmond, Clinton, Conn., assignor to
Underwood Corporation, New York, N. Y., a
corporation of Delaware

Application May 26, 1948, Serial No. 29,253

19 Claims. (Cl. 197—63)

1

This invention relates to typewriting machines and more particularly to devices in such machines for conveniently positioning carriage locating stops in desired positions by control means remote to the stops and conveniently accessible to the operator.

Devices of this general nature are old in the art and many are disclosed in expired patents, and are usually in the form of margin regulating devices.

One of the objects of the invention is to provide a remote-control stop positioning device which is durable, and reliable in operation.

It is another object of the invention to provide such a stop positioning device without addition of any appreciable weight to the typewriter carriage, wherefore the carriage is capable of letter-feeding at maximum speed, efficiently, and with a minimum of strain, noise and vibration.

It is a further object of the invention to provide a remote-control stop positioning device which can be manufactured at very low cost, and nevertheless is supreme in efficiency and performance.

It is a still further object of the invention to provide a simply constructed, light-weight, reliably operating device to selectively release one or another of two margin stops for adjustment to different margin-defining positions, the device including control means located so as to be conveniently and readily accessible to the operator at all times.

Many other objects and advantages of the invention will become apparent from a study of the accompanying drawings and a detailed description that follows.

The invention is shown and described in association with margin stops, but finds equally useful application to facilitate the setting of other kinds of stops such as, for example, tabulator stops.

Referring now to the drawings:

Figure 1 is a transverse sectional view of a typewriter carriage, including also certain portions of the stationary part of a typewriter, taken substantially along line 1—1 of Figure 4.

Figure 2 is a fragmentary plan view of a right-hand portion of the typewriter carriage, including a selective margin stop releasing control.

Figure 3 is a fragmentary front elevation of a line-end margin stop in association with a line-end signalling device.

Figure 4 is a skeletonized plan view of the typewriter carriage and portions of the machine

proper, the novel remote control stop positioning device being included in the showing,

Figure 5 is a left-hand sectional side elevation of a line-end margin stop including some immediately associated parts, in normal condition, and taken along line 5—5 of Figure 4.

Figure 6 is a view similar to Figure 5, and shows the same margin stop released for repositioning,

Figure 7 is a sectional view taken along line 7—7 of Figure 4, and depicts the left-hand margin stop held in a margin defining position,

Figure 8 shows the stop of Figure 7 released for repositioning,

Figure 9 is a right-hand end view of a rear portion of the typewriter carriage, showing specifically a control whereby the margin stops are releasable selectively for individual repositioning,

Figure 10 is a sectional front view of most parts illustrated in Figure 9, the section being taken substantially along line 10—10 of Figure 9, and

Figure 11 is a sectional plan view of a carriage return position defining margin stop held in a position on a supporting rack.

Referring now more specifically to Figure 1, a carriage, generally designated by the reference character 10, includes a grooved rail 11 which by means of anti-friction elements 12 is guided in a grooved trackway 13 that is part of the stationary framework of the machine. Said carriage includes spaced ends 14 rising from the carriage rail 11, and a platen roll 15 is turnably mounted in said carriage ends in a well-known manner.

Normally the carriage is under control of a letter-feed escapement comprising a holding dog 17 and a stepping dog 18, the holding dog 17 being normally in engagement with an escapement wheel 20. Said escapement wheel 20 is carried on a vertical shaft 21 carrying at its upper end a pinion 22 in engagement with a carriage supported rack 23. Said escapement wheel 20, the shaft 21 and the pinion 22, constitute a unit rotatively carried on the frame by means of brackets 24, 25, about the shaft axis. The carriage is urged to move in letter-feed direction, that is, rightwardly as viewed in Figure 4, by spring tension, as usual, by

means not shown, and incident to each typing or word spacing operation the escapement 17, 18 is vibrated, permitting a letter-feed movement of the carriage under urge of said spring tension, in the conventional manner.

The rack 23 constitutes part of a pivoted

structure including two side arms 30, each having a fulcrum 31 on an upstanding bracket 32 on the carriage rail 11. For locating the carriage quickly in any desired position, the rack 23 is adapted to be raised free from the pinion 22 by rocking said pivoted structure upwardly about said pivots 31. Such rocking is effected at will by operating a carriage release lever 33 fulcrumed at 34 on the carriage and connected by means of a link 35 to said rocking structure. A spring 36 connected to an ear on the link 35 is instrumental to maintain the rack 23 releasably in mesh with the pinion 22.

To the rear of the platen there rises on an upward and rearward incline, between the two carriage ends 14, a usual paper shelf 37. This shelf is supported at each lateral end by a bracket 38, see Figures 1 and 4, each bracket having a rear leaf 40 reaching behind a rear flange of the adjacent carriage side plate 14 for a screw 41 to secure it thereto. Each bracket 38 includes also a rest 37a for the paper shelf 37.

Carried by and extending along the extreme rear of the carriage is an inverted U-shaped bar 42 constituting a rack for supporting, at letter-space intervals, key-settable tabulator stops 43. This rack and the key-settable stops thereon are of known design, and whatever tabulator stops 43 may have been set, are adapted to be engaged by tabulator counterstop means 44 under tabulator key control, not shown, said counter-stop means being shown in Figures 1 and 4 to protrude from a housing 49 constituting part of the framework of the machine. The U-shaped rack 42, at the left end of the carriage, is supported by a bracket 45 which is fastened to a flange 46 of the left carriage end by a screw 47, the rack being secured by a screw 48 to said bracket. The right end of the rack is similarly supported on a bracket 50, but this latter bracket, see Figure 4, is formed to secure it to the right carriage end by the same screw 41 which serves to hold the bracket 38.

Margin stop device

To this point the mechanism which has been described is conventional typewriter structure, and, directing attention temporarily more particularly to Figure 4, it will be seen that on the carriage there extends in front of the tabulator rack 42 a round bar 52 which along its rear side and its front side affords opposite rows of teeth, or racks 53 and 54, respectively, the individual teeth of the rack 53 having sides which are square to the rod, and the teeth of the rack 54, for reasons to be pointed out later, being of buttress form. Upon said rod 52 there is carried a left margin stop 1L, and a right margin stop 1R, such stops comprising block-like bodies 2L and 2R, respectively, having cylindrical extensions 3L and 3R, respectively, reaching toward each other. Said margin stops 1R and 1L are provided with smooth bores 69 extending concentrically of said cylindrical extensions, fully through the stops, and the rod 52 supports both said stops by extending through the bores thereof. The rod 52 is supported pivotally on the carriage, at the right end of the carriage in the bracket 50, and at the left end of the carriage in a forward extension of bracket 45. Specifically, the left end of the rod 52 has a reduced end 55 reaching through and pivoted in the bracket extension 45, and carrying a retainer collar 56 outside of said bracket extension, whereby the

rod 52 is longitudinally restricted to partake in all carriage movements.

The margin stops 1L and 1R have each a vertical rear face 66 which in conjunction with the broad front face of the tabulator stop carrying bar 42 constricts the stop against turning about the axis of the rod 52.

At the right-hand end of the carriage there is associated with the rod 52 a control member or manipulative arm 61 headed by a round finger piece 62. Normally this manipulative arm is vertically positioned, as seen in full lines in Figures 1, 2, 4, 5, 7 and 9, and thereby normally determines the pivotal position of the rod 52 so that the rows of rack teeth 54 and 53 thereon stand respectively fore-and-aft of the machine as seen in Figures 1, 4, 5 and 7. With the rod 52 so positioned, both the margin stops are coupled or locked to the rod in specific margin-defining positions, in a manner presently to be described.

On the right margin stop 1R, see Figure 5, a dog 4R is pivotally supported for movement into and out of engagement with the rack 53, by a pin 5R, located to the rear and above the rod 52, and may be in engagement in any of the notches in the rack 53. A slot 58 in the stop accommodates the dog for free pivotal movement. A compression spring 6R contained in a socket hole 7R pushes against the upper end of the dog 4R so as to bias its lower end into locked engagement with the rack 53. Thus the right margin stop 1R is normally locked in a specific margin-defining position along the rod 52.

The left margin stop 1L, see Figures 4, 7 and 11, has a dog 4L which normally is in engagement in any of the notches in the row of buttress teeth 54. This dog 4L is accommodated in a slot of its stop like the dog 4R, and is pivoted in its stop by a pin 5L located in front of and above the rod 52. A spring 6L accommodated in a hole, similarly to the spring 6R, presses the dog 4L into stop-locating engagement with the row of buttress teeth 54.

For reasons which will be made clear later, the margin stop 1L has an additional dog 8L which normally is in engagement with the rack 53. This dog 8L has a pivot pin 9L which is located below the rod 52 and a spring 10L presses its upper end resiliently into toothed engagement with the rack 53.

In establishing the writing-line margins the margin stops 1L and 1R cooperate with a counterstop 67 which protrudes upwardly through a perforation 68 in the housing 49 of the machine framework located below the margin stops. Said counterstop 67 is in the form of an upright element normally adapted to pivot about a point 69 to the limit permitted by the perforation 68, against the tension of a fairly strong spring 70 urging said element upwardly and rightwardly. The left margin stop 1L cooperates with the counterstop 67 by means of a face 71, see Figures 4 and 11.

Referring to Figure 11, it will be seen that the dog 4L fits the notches in the rack 54 while, on the other hand, the dog 8L is narrower than the notches of rack 53 and has a loose fit between the teeth. Incidental to the arrest of the carriage during carriage return, the stopping impact is transmitted by the dog 4L, to the buttress tooth of rack 54 which is to the left thereof, but, even in machines designed for small letter-feed, this dog and any of the buttress teeth can easily withstand the strain by reason of their

buttress tooth form. The dog 8L may take some of the carriage arresting load, but primarily serves to lock positively the margin stop 1L normally against leftward displacement on the carriage, and also to keep the left margin stop reliably interlocked with the rod 52 while the right margin stop is being adjusted, as will yet become evident.

The left side face 72 of the margin stop block 2R of stop 1R cooperates with the counterstop 67 through the intermediary of an interponent 13 carried on the block, and the purpose of which will be brought out later.

The margin stop 1L, of course, constitutes a return limiting stop, the return limit being established by the stop face 71 thereon engaging the counterstop 67. The margin stop 1R, in the typing of a line, through the interponent 13 carried thereon, at the approach of the line end, see Figure 3, will first operate a line-end signalling device comprising a lever 75 pivoted at 76, the lever having a bell-ringing end 77 adapted to strike within a bell globe 78 after first displacing the lever anti-clockwise of Figure 3, and incidental to riding clear thereof to the left. The spring 80 resiliently urges the bell lever 75 to the normal position shown in Figure 3, and supplies the bell-ringing power. About six letter-feed advances of the carriage leftwardly after the sounding of the bell, the interponent 13 on stop 1R will cause a leftward displacement of the counterstop 67 against the tension of the counterstop spring 70, and such displacement, through operation of a line-end locking lever 75 pivoted at 76, will incapacitate the typing mechanism in a manner well known in the art. However, the operator may type additional characters upon operation of a margin release control, not shown, which lowers the counterstop 67 below cooperative range of the margin stops. Typing to the left of the position defined by the stop 1L is also possible by use of the margin release control. The margin stops 1R and 1L have each a usual cam face at their bottom, and these faces, by riding over and depressing the counterstop 67, allow the carriage to be brought readily back within the defined marginal positions. In doing this with reference to the stop 1L, the toothed engagement with the bar afforded by the dog 8L insures against shift of the stop rightwardly which may be permitted by the dog 4L.

Margin stop adjustment

The margin stops 1L and 1R are selectively releasable from the supporting rod 52 by movement of the manipulative arm or control 61 respectively forwardly and rearwardly to abnormal positions. If moved rearwardly to the abnormal position seen in Figure 6, the resultant turning of the rod 52 will cause the dog 46 to be cammed clear of the rack 53, out of the tooth notch, and onto a smooth longitudinal surface directly above such rack. However, this rearward positioning of the manipulative arm 61 and the consequent turning of the rod 52 is not sufficient to free the left margin stop 1L from toothed interlock with the rod 52. This will be perceived from Figure 6, wherein the dog 8L for the left margin stop 1L is shown in dot-and-dash lines, and, though partially crowded outwardly, is still effective to hold its associated margin stop locked to the rack 53 and thus located on the rod 52.

In the embodiment of the invention shown, the margin stops are resiliently urged toward each other, by a device comprising a spring drum 81

carried by means of a stud 82 on the margin stop 1R, having a flexible element or string 83 wound thereupon and extending to and connected to the left margin stop by means of a stud 84. A clock spring 85 within the drum 81 and having an inner anchorage on said stud, supplies the power for the drum to wind the string 83.

It will thus be seen that when the manipulative control 61 is moved rearwardly, the stop 1R will be drawn resiliently leftwardly to encounter the counterstop 67 (if not already located thereagainst), and thereupon adjustment of the stop 1R can be effected by merely operating the aforementioned carriage release lever 33 and moving the carriage, the margin stop remaining throughout in abutment with the counterstop, that is stationary with respect to the machine frame. If then the manipulative control 61 is restored to normal position, the margin stop 1R will become relocked along the rod in the desired new position by means of the dog 4R entering the proper notch in the rack 53 under tension of the dog spring 6R. In conjunction with effecting the adjustment of the line-end margin stop 1R, it is to be noted that the spring power urging this margin stop 1R leftwardly is inferior to the power of the spring 70 urging the counterstop rightwardly, whereby the relocation of the margin stop 1R is controlled by the counterstop 67 always while the latter is in its rightward position shown in Figure 4. Moreover, it follows that the new position given the margin stop 1R is representative always of the last possible typing position of the carriage before the typing mechanism is incapacitated through leftward displacement of the counterstop 67, as pointed out before.

When the manipulative control 61 is moved forwardly, from normal upright position to the full line, abnormal position shown in Figure 8, both the dogs 4L and 8L associated with the margin stop 1L will be cammed outwardly by the rod 52 against the tension of their light dog springs to free them from interlock with the racks 53 and 54. Both said dogs are then clear of their associated racks and bear then resiliently against smooth longitudinal surfaces on the rod 52 as shown in Figure 8, wherefore the associated margin stop 1L is free for movement along the supporting rod 52, and the flexible band intermediate the two margin stops will then cause movement of the margin stop 1L against the counterstop 67. The desired location of the margin stop is then obtained by merely moving the carriage to the desired return limit position and then restoring the manipulative control 61 to normal position, this causing the dogs to relock the margin stop in the desired position.

It should be noted from Figure 8 that while adjustment is effected of the left margin stop 1L, the right margin stop 1R remains locked to the rod 52 through the dog 4R which, although partly displaced outwardly by the turning of the rod 52, nevertheless remains controllingly in its engaged tooth notch.

The manipulative control 61 has a device associated therewith which resiliently biases such arm to restore to its normal, upright position. In this connection more specific reference is made to Figures 2, 4, 9 and 10. First referring particularly to Figure 10, it will be seen that the rod 52 outside of its supporting bracket 50 has a reduced end 86 whereupon there is held, as by a set screw 87, a collar 88. This collar has a broad vertical groove 89 to confine the lower end of the manipulative arm 61 which has a perforation 90 to

locate it upon a shouldered stud 91 screwed in the reduced shaft end 86. Said stud has a large head 92, between which and the control arm 61 there is provided a compression spring 93 resiliently positioning the control arm normally flatly against the base of the groove 89, but permitting some swinging displacement rightwardly and leftwardly as indicated in Figure 10.

Upon the right side 14 of the carriage frame there is secured, as by screws 94, a bracket 95 affording individual pivotal supports 96 for two arms 97 which by a spring 98 are drawn toward each other to definite positions, giving normally the control arm 61, and therefore the rod 52, a definite pivotal position. The said arms 97, in their normal positions, have toes 99 bearing against a shelf 100 of the bracket 95. The upper ends of the arms 97 have horizontal ears 101 to provide broad contacting faces for the arm 61. Following operation of the manipulative arm 61 either forwardly or rearwardly, and upon subsequent release thereof, the control arm 61 will automatically reassume normal, that is, upright position under the action of the spring-influenced arms 97.

The extremes to which the control arm can be swung forwardly and rearwardly are established by limits afforded in a bracket 102, by respectively the forward end of a slot 103 and a rearward end of a slot 104 in such bracket, see particularly Figures 2 and 9. As seen in the plan view of Figure 2, the slots 103 and 104 are out of line with respect to each other and have a connecting clearance 105 whereat the control arm 61 is normally restricted against direct rearward or direct forward movement. In order to move the control arm 61 rearwardly for effecting an adjustment of the right margin, the operator is first required to give the arm 61 deliberately a rightward thrust to line it up with the slot 104. The lever 61, of course, is capable of rightward and leftward displacement by reason of its being accommodated in the collar groove 89, and for the reason that the spring 93 is yielding.

To effect an adjustment of the left margin stop the operator is first required to move the control arm 61 deliberately leftwardly into alignment with the slot 103, and then forwardly. Upon release, either after forward or rearward displacement, the control arm will be spring-restored and will always be intercepted and held in the connecting clearance 105, as seen in Figure 2. It will be noted that in so assuming normal position there cannot be an overthrow beyond the normal position. The bracket 102 has a vertical portion 106 which at one point is secured to the adjacent carriage end by the screw 94 and in another place by screw 107. The requirement for rightwardly and leftwardly displacing the lever 61 respectively in connection with effecting respectively a right and left margin stop adjustment is to avoid confusion in the mind of the operator. Indices "R" and "L" are provided in close proximity to the lever 61, on a conventional part 114 carried by the right carriage end.

It has been said that the right margin stop 1R cooperates with the counterstop 67 through the medium of an interponent 73. This interponent, see Figures 3 and 4, is a rearwardly bent-off part of a lever 108 which is pivotally carried on the margin stop 1R by the stud 82, and the latter of which supports the spring drum 81. Said lever includes a weighted arm 109 always tending to keep the interponent 73 against the margin stop face 72. It will now be seen that

whenever the margin stop 1R has passed beyond line-end signalling position, the interponent 73, during an ensuing carriage return movement, will encounter the bell-ringing lever 75, but in doing so will swing idly thereover upwardly away from the margin stop face 72, wherefore the line-end signalling device will then not function.

The flexible element 83 which extends between the spring drum and the left margin stop, just 10 leftwardly of the drum, passes over a small sheave 111 rotatively carried on a plate 112 that is held fast on the margin stop 1R by a shoulder of the screw stud 82.

The limits to which the margin stops are adjustable on the carriage are defined by abutment screws 113 carried upon opposite ends of the carriage.

The invention is not limited to margin stop adjustment, but is broadly applicable to selective 20 release of carriage stops by remote-control means in general, the broad principle residing in the provision for selective, remote-control release of stops through rearrangements of such stops and rack means in transverse aspect to the direction 25 in which the rack means extend. Moreover, the invention is capable of many embodiments without departing from the fundamental conceptions and features thereof.

What I claim is:

30 1. In a typewriting machine having a carriage movable on a frame; adjustable stop means for the carriage comprising, a bar extending parallel to the carriage, a stop carried on said bar for adjustment to different carriage stopping positions therealong, means to give said bar different rotative positions about an axis lengthwise of the bar, means extending lengthwise of said bar to confine said stop against rotation with the bar about said axis, rack means extending lengthwise on said bar, and tooth means on said stop respectively engageable and disengageable from said rack means by giving said bar different rotative positions about said axis, whereby said stop is adapted to be adjusted and locked in different positions lengthwise of said bar.

2. In a typewriting machine having a carriage movable on a frame, adjustable stop means for the carriage, comprising, a stop, a bar supporting said stop and having two rows of teeth therealong, the teeth of one row being of buttress form, dog means on said stop mounted for movement into and out of engagement with the rows of teeth, means biasing said dog means into engagement, the dog means in association with the buttress teeth being able to withstand heavy carriage arresting loads in one direction of carriage movement, and the dog means in association with the other row of teeth serving normally to detent the stop against displacement in the opposite direction, and means to turn said bar relatively to the stop about an axis extending lengthwise of the bar to cause said dog means to clear said rows of teeth and ride onto a bar surface which is smooth lengthwise of the bar, thereby to free the stop for adjustment.

3. In a typewriting machine having a carriage movable on a frame; adjustable stop means for the carriage comprising, a bar, two stops carried on said bar for individual adjustment to different carriage stopping positions therealong, means including a control means remote from said stops to give either of said stops relatively to said bar different positions about an axis which lies lengthwise of the bar, rack means

lengthwise on said bar, and tooth means on each of said stops individually engageable and disengageable from the rack means respectively by giving said stops and bar different relative positions about said axis, whereby respectively to lock and release either of said stops for effecting an adjustment thereof along said bar.

4. In a typewriting machine having a carriage movable on a frame, adjustable stop means for the carriage, comprising, a bar, two stops carried on said bar for individual adjustment therewith, counterstop means for said stops, said bar and said counterstop means being oppositely on the frame and the carriage, means including control means remote from said stops to give either of said stops relatively to said bar different positions about an axis which is lengthwise of the bar, rack means lengthwise on said bar, tooth means on each of said stops individually engageable and disengageable from the rack means respectively by giving said stop and bar said different relative positions about said axis, whereby respectively to lock and release either of said stops from the bar, and means to move the respective stops, as they are released, along the bar in one direction against the counterstop means.

5. In a typewriting machine having a carriage movable on a frame; adjustable stop means for the carriage, comprising, two stops, a common supporting bar for said stops, means pivotally supporting said bar, rack means on said bar, tooth means on each stop normally cooperative with said rack means to lock the stops in individually adjusted positions along the bar, and control means associated with said bar to give it selectively one or another of two abnormal pivotal positions, in one of which the rack means frees the tooth means of one stop, and in the other of which the rack means frees the tooth means of the other stop whereby to facilitate adjustment of either one of the stops while the other stop remains locked lengthwise of the rod.

6. In a typewriting machine having a carriage movable on a frame; two carriage arresting stops, and means to support said stops so that said stops are selectively releasable for adjustment to different positions, comprising, unitary rack means extending parallel to the carriage, tooth means on each stop normally cooperating with said unitary rack means to hold each stop in individually adjusted position lengthwise of the unitary rack means, and means including control means remote from said stops to effect transversely of the unitary rack means, selectively one or another relative arrangement between the said tooth means and the unitary rack means, the tooth means of the individual stops being cooperatively arranged with respect to the unitary rack means so that in each of the two said transverse relative arrangements the tooth means of respectively only one or the other stop are freed from the unitary rack means.

7. In a typewriting machine having a carriage movable on a frame; two carriage arresting stops, counterstop means for said stops, said stops and counterstop means being oppositely on the frame and the carriage, a bar to support said stops selectively releasably for adjustment to different positions and having rack means extending parallel to the carriage, tooth means on each stop normally cooperating with said rack means to hold each stop in individually adjusted position lengthwise of the bar, means including control means remote from said stops to effect trans-

versely of the bar, selectively, one or another relative arrangement between both the said stops and the bar inclusive of said rack means, the tooth means of the individual stops being cooperatively arranged with respect to the rack means so that in the two said transverse relative arrangements the tooth means of respectively only one or the other stop are freed from the rack means, and means to move said stops as each is released into abutting relation with the counterstop means.

8. In a typewriting machine having a carriage movable on a frame; two carriage arresting stops, and means to support said stops so that said stops are selectively releasable for adjustment to different positions, comprising, rack means extending parallel to the carriage, tooth means on each stop normally cooperating with said rack means to hold each stop in an individually adjusted position lengthwise of the rack, and means to displace said rack means transversely of its length, oppositely to one or another position, said rack means and tooth means being cooperatively arranged for the rack means when displaced to one of said positions to clear the tooth means of one stop, and for the rack means when moved to the other position to clear the tooth means of the other stop.

9. In a typewriting machine having a carriage movable on a frame; adjustable stop means for the carriage, comprising two stops, a common supporting bar for said stops, dog means on each stop resiliently urged toward the bar, said bar having rack means formed lengthwise therewith and said dog means being normally engaged in the rack means of the bar, and means including control means remote from said stops to give selectively either one of said stops relatively about the bar an abnormal position which will cause the dog means thereof to ride off the rack means onto a smooth surface on the bar while the dog means of the other stop remains in stop holding engagement with the rack means.

10. In a typewriting machine having a carriage movable on a frame; two carriage arresting stops, and a bar supporting said stops so that said stops are selectively releasable for adjustment to different positions, comprising, rack means extending parallel to the carriage, tooth means on each stop normally cooperating with said rack means to hold each stop in individually adjusted position lengthwise of the rack, and means to rock said rack means transversely of its length, oppositely to one or another position, said rack means and tooth means being cooperative, for the rack means when rocked to said one position to clear the tooth means of one stop, and for the rack means when rocked to the other position to clear the tooth means of the other stop.

11. In a typewriting machine having a carriage movable on a frame, two margin stops, and means to mount and adjust said margin stops, comprising, a common supporting bar for both said stops having lengthwise thereon one rack composed of buttress teeth and another rack composed of substantially square-shaped teeth, dog means on one stop associated with said first rack, dog means on each one of said stops associated with said other rack, spring means to bias all said dog means toward the bar to engage normally their associated racks, thereby to hold such stops adjusted, and means to rock said bar oppositely to one or another abnormal position, the dog means associated with one stop

being disengageable by the rocking of the bar to one abnormal position, and the dog means of the other stop being disengageable by the rocking of the bar to the other abnormal position.

12. In a typewriting machine having a carriage movable on a frame; two margin stops, and means to support and control said margin stops so that they are selectively releasable for movement to different margin defining positions, comprising, a control member remote from said stops and movable transversely of the carriage, oppositely to release selectively one or the other margin stop for adjustment, and means for mounting and restricting said control member to compel an operator to give it respectively a slight leftward or a slight rightward movement preparatory to moving it transversely of the carriage for releasing respectively one or the other margin stop.

13. In a typewriting machine having a carriage movable on a frame; a left and a right margin stop mounted on the carriage and selectively releasable for adjustment to different margin defining positions, and means to selectively release said margin stops, comprising, a control member at one end of the carriage capable of manipulation transversely of the carriage from a normal position oppositely to one or another abnormal position, thereby to release respectively one or the other margin stop, means to lend said control member capacity for some displacement on the carriage leftwardly and rightwardly against resilient resistance tending to restore it, and means to restrict said control member to necessitate giving it a deliberate leftward and a deliberate rightward displacement respectively preparatory to manipulating it to one or the other of said abnormal positions.

14. The invention set forth in claim 13, and said restricting means including means for blocking movement of the control member directly between the two said abnormal positions without the operator giving the control member a deliberate leftward or a deliberate rightward displacement.

15. The invention set forth in claim 13, including means to intercept and hold the control member upon its return to normal position, pending the impartation thereto of a new deliberate leftward or rightward displacement.

16. In a typewriting machine having a carriage movable on a frame; adjustable stop means for the carriage comprising, a bar, a stop carried on said bar turnably relatively thereto about an axis lengthwise of the bar for adjustment of the stop to different carriage stopping positions along the bar, means to give said stop and bar different relative positions about said axis from a location remote from said stop, said last means comprising, means to confine said stop normally against turning relatively to said bar, and means to give said confining means and said bar different relative positions about said axis, rack means extending lengthwise on said bar, and tooth means on said stop respectively engageable and disengageable from said rack means by giving said confin-

ing means and said bar said different relative positions about said axis, whereby said stop is adapted to be adjusted and locked in different positions lengthwise of said bar.

17. In a typewriting machine having a carriage movable on a frame; adjustable stop means for the carriage comprising, a bar, a stop carried on said bar turnably relatively thereto about an axis lengthwise of the bar for adjustment of the stop to different carriage stopping positions along the bar, counterstop means for said stop, said stop and counterstop means being oppositely on the frame and the carriage, means to give said stop and bar different relative positions about said axis from a location remote from said stop, said last means comprising, means to confine said stop normally against turning relatively to said bar, and control means to give said confining means and said bar different relative positions about said axis, rack means extending lengthwise on said bar, tooth means on said stop respectively engageable and disengageable from said rack means by giving said confining means and said bar different relative positions about said axis, and means to move said stop automatically against said counterstop means as the tooth means of the stop is disengaged from the rack means.

18. In a typewriting machine having a carriage movable on a frame; two margin stops, and means to support and control said margin stops so that they are selectively releasable for movement to different margin defining positions, comprising, a control member remote from said stops and movable transversely of the carriage, oppositely from a normal position to release selectively one or the other margin stop for adjustment, means for mounting and restricting said control member to compel an operator to give it respectively a slight leftward or a slight rightward movement preparatory to moving it transversely of the carriage for releasing respectively one or the other margin stop, and spring-means to restore said control member to normal position whenever it is released after a stop releasing movement.

19. A margin stop assembly for typewriters comprising a rod, means for rotatably supporting the rod on and parallel with the carriage of a typewriter, a margin stop slidably mounted on the rod adapted to be engaged by a carriage stop of the typewriter, resilient means normally urging the margin stop away from one end of the rod to the opposite end thereof, and means co-acting between the margin stop and the rod to lock the former on the latter, said rod being rotatable to release the stop.

WILLIAM F. HELMOND.
